CLAIM

The ornamental design for a wheel locator, as shown and described.

DESCRIPTION

FIG. 1 shows a side view of our claimed design in use. FIG. 2 shows a perspective view of our claimed design in use.

FIG. 3 is an enlarged rear, bottom and left side perspective view of our claimed design, the rear, bottom and right side perspective view being a mirror image.

FIG. 4 is an enlarged fragmented left side view thereof, the right side view being a mirror image.

FIG. 5 is an enlarged fragmented bottom view thereof; and, FIG. 6 is an enlarged fragmented front view thereof.

The broken line showing in FIGS. 1 and 2 is for illustrative purposes only and forms no part of the claimed design. The surface or portions of the article not shown in the drawing or described in the specification form no part of the claimed design.
